Attorneys.

UNITED STATES PATENT OFFICE

158,411

LINK CHAIN FOR A BRACELET OR THE LIKE

John F. Sand, Newark, N. J., assignor to Gemex Company, Union, N. J., a corporation of New Jersey

Application October 10, 1949, Serial No. 5,406

Term of patent 7 years

(Cl. D45—16)

To all whom it may concern:

Be it known that I, John F. Sand, a citizen of the United States and a resident of Newark, Essex County, New Jersey, have invented a new, original, and ornamental Design for a Link Chain for a Bracelet or the like, of which the following is a specification, reference being had to the accompanying drawing forming part thereof, in which

Fig. 1 is an edge view of a link chain for a bracelet or the like of this design;

Fig. 2 is a top plan view of Fig. 1; and,

Fig. 3 is a bottom plan view of Fig. 1.

I claim:

The ornamental design for a link chain for a bracelet or the like, as shown.

JOHN F. SAND.
